UNITED STATES PATENT OFFICE.

JEFF DAVIS PHILYAW, OF MERIDIAN, MISSISSIPPI, ASSIGNOR OF ONE-SIXTH TO THOMAS W. ELKIN, ONE-SIXTH TO MAESHAL L. HUFFMASTER, AND ONE-SIXTH TO THOMAS D. HARBOUR, ALL OF MERIDIAN, MISSISSIPPI.

DOORBELL AND BURGLAR ALARM.

Application filed July 2, 1928. Serial No. 289,928.

An object of the invention is to provide a simple and efficient alarm mechanism which can be easily and readily installed in banks, stores and residences as a protection against 5 burglary. In addition to its service as a burglar alarm, the device can also be used in the capacity of a door bell.

With the above and other objects in view, the invention consists in the novel arrangement, construction and association of parts, 10 as hereinafter set forth and described, reference being had to the accompanying drawings, where,

Figure 1 is a plan view of the alarm;
15 Figure 2 is a sectional view on line 2—2 of Figure 1;

Figure 3 is a side view of the alarm;

Figure 4 is a view showing the manner of 20 installing the invention as a burglar alarm in a resident; and,

Figure 5 is a view showing the burglar alarm as installed in a bank.

The alarm sounding mechanism embodies a supporting panel 1 of wood or other suitable material upon which is fixed a bell 2 and a spring motor 3 for operating the bell striker 4. The spring motor and striker mechanism may be of any conventional type and is adapted, for the purposes of the invention, to oscillate the striker continuously about its pivot 5 until the spring is fully run down or until movement of the striker is checked, as hereinafter explained. A lever 6 is pivotally mounted at 7 on the panel and extends cross-wise of the latter between the bell and the spring motor, holes 8 and 9 being provided in the opposite ends of the lever for the attachment thereto of operating cords or cables. Rigidly fastened to one arm of lever 40 6, so as to extend angularly therefrom in a position to engage the striker 4, is a stop or check member consisting of a flat resilient spring 10 having its free end 11 bent, as shown. When the device is installed, the mechanism is concealed by a cover casing 12 fastened to the panel.

When used as a door bell, the panel 1 is fastened to the door facing on the inside of the residence, and an opening is made in the 50 facing in direct line with an opening 13 in the panel. A push button 14 is slidably fitted in the openings from the outside of the residence with its inner end contacting with the spring check member 10. The lever 6 is nor-

mally positioned, as shown in Figure 1, so 55 that the bent end 11 of check member 10 bears against the striker 4 and prevents it from oscillating under the influence of the spring motor. When the push button is forced inwardly, it flexes the check member 10 out of engagement with the striker and thus permits the latter to operate against the bell. Upon release of the push button, the check member springs back into the path of the 60 striker and prevents further movement of 65 the same.

When using the device as a burglar alarm for a dwelling, the panel 1 is preferably mounted upon a window facing, and an operating cord or cable 15 is connected to the lever 70 6. As shown in Figure 4, the operating cord may be anchored at one end 16 to the door casing 17 and extended across the door and behind a pulley 18 on the opposite casing, from whence it is passed across one or more 75 windows 19, to which it is connected at 20. It is also connected, as shown at 21, to the lever 6 of the alarm. Hence, any opening movement of the door or windows will exert a pull on the cord that will result in the lever 6 being 80 so moved about its pivot as to draw the check 10 back from the striker 4 a distance sufficient to enable the latter to operate fully and ring the bell. The cord may be formed of detachable sections to permit disconnection of the 85 cord during the day.

A slightly different arrangement is used when installing the device in a bank as an alarm for day robbery. In such an instance, the alarm is preferably located upon the roof, 90 as shown in Figure 5, and a single operating cord 22 connects with the lever 6 and leads down through the roof into the bookkeeper's balcony 23, extending substantially the length of the balcony, then down and under the 95 flooring 24 in front of the tellers' cages and under the offices, being anchored, as shown at 25. Suitable pulleys 26 are arranged to support and guide the cord in its movements and pull ropes 27 are attached to the cord for the 100 convenience of the bookkeeper in the balcony.

In the lobby and office, push buttons 28 are located at convenient places in the flooring, and when depressed by the foot will exert 105 pull on the operating cord sufficient to move the lever 6 and release the striker mechanism, whereby the alarm will be sounded.

Variations may be resorted to within the

scope of the invention and portions of the improvements may be used without others.

Having thus described the invention, what is claimed as new is:

- 5 1. An alarm sounding mechanism including a support, a bell fixed thereon, a bell sounding mechanism including a striker adapted to be oscillated about its pivot, a lever pivotally mounted on the support and 10 having holes in its opposite ends for the attachment thereto of operating cords or cables, a spring check member fastened to one arm of the lever in a position to engage and prevent operation of the striker when the said 15 arm is moved in the direction of the latter, and a slideable push button extending through the support and adapted when forced inwardly to move the check member out of engagement with the striker.
- 20 2. An alarm sounding mechanism including a supporting panel, a bell mounted thereon, a pivotally mounted bell striker, clock work for oscillating the striker on its pivot, a check member consisting of a flat spring 25 anchored at one end and having its free end

normally engaged with the striker to prevent operation thereof, and a push button slidably fitted in an opening in the panel with its inner end bearing against said check member; said push button being adapted when forced inwardly to flex the said check member out of engagement with the striker.

3. A combined door bell and burglar alarm consisting of supporting panel, a bell mounted thereon, a striking mechanism including a bell hammer, a centrally pivoted lever mounted on the panel and adapted to be connected at its opposite ends with operating cords, a check member carried by and projecting from one arm of the said lever, said lever being normally positioned to engage the said check member with the said bell hammer to prevent movement of the latter, and a push button slideable against the said check member for moving it out of engagement with the 45 said bell hammer.

In witness whereof, I hereunto affix my signature.

JEFF DAVIS PHILYAW.
